URIAS B. KLINE, OF REAMSTOWN, PENNSYLVANIA.

Letters Patent No. 104,039, dated June 7, 1870; antedated June 3, 1870.

IMPROVEMENT IN JOINTED SPRING-GUARD.

The Schedule referred to in these Letters Patent and making part of the same.

I, URIAS B. KLINE, of Reamstown, in the county of Lancaster and State of Pennsylvania, have invented certain Improvements in Staying Elliptic Springs on Vehicles, of which the following is a specification.

The nature and object of my invention is to guard against the lurching or twisting of elliptic springs so liable to break them on striking a large stone or gutter in the road, to which end various devices have been applied, as guards, braces, and guides, differing substantially from my jointed guard or stay-rod.

The accompanying drawing clearly shows the construction and application of my invention.

Figure 1 shows the construction of my triple-jointed stay-rod A B C D, with its foot-plate E and upright F. This plate is bolted firmly to the coupling G, fig. 2. The three shouldered joints of the rod are marked *a*, *b*, and *c*.

Figure 2, a side view illustrating the operation in part.

The dotted lines show the relative position when the spring is up, and when pressed down in a vertical course indicated by the dotted lines from *d* to *d'*.

The terminal piece D is so constructed as to adapt it, with the supporting cross-piece *d*, to the under side or top of the spring H, and will yield sufficiently to allow the springs to play freely up and down on smooth roads, and yet stay it as firmly as a fixed brace.

In order to prevent swagging laterally, twisting, or to swing backward and forward, from which cause

the most damage is done to springs, the joints *a* *b* *c* are brought into requisition in proportion as the connection with the spring is borne down more or less, and yield to accommodate the rod or stay to the vertical motion of the springs H.

The upright rest F is to check the joint B to its action within fixed limits between the shouldered joint *a* and said rest or check F.

I have tried the application by attaching the stay or jointed guard to the front springs H of a vehicle, and bolting the foot-piece E firmly to the coupling-pole G, with the happiest results. It allows a free vertical motion, and effectually guarding and preventing the springs from twisting laterally, and, consequently, of marked utility; besides, when ascending or descending a hill, this kind of brace prevents the pressure on the springs of the weight within the vehicle or the body of the vehicle itself, when inclined according to the angle or inclination of the hill, and thereby perform an important function to relieve the springs from such pressure in front or rear.

What I claim as my invention is—

The combined jointed stay or guard A B C D, with its foot-piece E F, applied in the manner and for the purpose specified.

URIAS B. KLINE.
